UNITED STATES PATENT OFFICE

163,524

LAMP

Edward L. Kulczycki, St. Louis, Mo.

Application November 30, 1949, Serial No. 6,326

Term of patent 14 years

(Cl. D48—20)

To all whom it may concern:

Be it known that the undersigned, Edward L. Kulczycki, a citizen of Poland, residing in St. Louis, Missouri, has invented a new, original, and ornamental Design for a Lamp, of which the following is a specification, reference being had to the accompanying drawing, forming a part thereof, in which:

Fig. 1 is an elevational view of a lamp showing my new design.

Fig. 2 is a top plan view thereof; and

Fig. 3 is a front elevational view thereof.

I claim:

The ornamental design for a lamp, substantially as shown.

EDWARD L. KULCZYCKI.
